DRAWING COMPASS

Robert Welch, Chipping Campden, England, assignor to
W. J. Harris (Birmingham) Limited, Stafford, England

Filed Jan. 11, 1971, Ser. No. 105,774

Term of patent 14 years

Int. Cl. D19—06

U.S. Cl. D52—6 B

FIG. 1.

FIG. 2.

FIG. 3.

FIG. 4.

FIG. 1 is a front elevational view of a drawing compass showing my new design.

FIG. 2 is a side elevational view of the compass.

FIG. 3 is a side elevational view of the compass taken from the opposite side to that shown in FIG. 2.

FIG. 4 is a fragmentary underneath plan view of the compass in the direction of arrow A of FIG. 1.

I claim:

The ornamental design for a drawing compass, substantially as shown.
